(57) **CLAIM**

The ornamental design for a tube light aging equipment, as shown and described.

DESCRIPTION

FIG. 1 is a top plan view of a tube light aging test equipment showing my new design;

FIG. 2 is a bottom plan view thereof;

FIG. 3 is a left side elevational view thereof;

FIG. 4 is a right side elevational view thereof;

FIG. 5 is a front elevational view thereof; and

FIG. 6 is a rear elevational view thereof; and,

FIG. 7 is a perspective view thereof.

The shade lines (straight solid lines) in the figures show surface contour but not surface ornamentation. The broken lines are environmental and form no part of the claimed design. One novel design feature of the present invention is that the tube light aging test equipment of present invention is vertically-configured or upright structured, which thereby is different from conventional tube light aging test equipments that are horizontally configured and structured to occupy a significant amount of floor space or footprint; thus, the tube light aging test equipment of present invention does not occupy significant amount of floor space or footprint, and at the same time is also aesthetically pleasing as a whole. The tube light aging test equipment can be used for testing aging quality of a plurality of tube lights that are spatially and stackingly arranged and hung in the tube light aging test equipment as shown in both front elevation view and rear elevation view as broken line circular structures.
